UNITED STATES PATENT OFFICE.

ARTHUR J. CHARLTON, OF WESTFORD, MASSACHUSETTS.

SQUEEZE-ROLL.

1,149,551.

Specification of Letters Patent. Patented Aug. 10, 1915.

Application filed July 17, 1912. Serial No. 709,883.

To all whom it may concern:

Be it known that I, ARTHUR J. CHARLTON, a citizen of the United States, residing at Westford, in the county of Middlesex and 5 Commonwealth of Massachusetts, have invented a new and useful Improvement in Squeeze-Rolls, of which the following is a specification, accompanied by drawings forming a part of the same.

10 My invention relates to squeeze rolls and more particularly to that class of squeeze rolls which are used in connection with washing and other like machines for expressing liquids from various textile materials such as yarn. The rolls are generally mounted in pairs in any well known manner, and it is customary to make one of the rolls of a pair with a yielding or compressible covering and the other roll of the pair with 15 an unyielding surface, although the surface of both rolls may be compressible if desired. The yielding covering referred to is necessarily of a more or less soft material, preferably rubber, and is, therefore, incapable of always withstanding without damage the great strains resulting from the more or less frequent bunching of the textile material being operated upon as it passes between the rolls. It is, therefore, necessary 20 at times to make certain replacements or repairs of more or less of the damaged covering and the main object of the present invention is to provide a pair of rolls of the type referred to, one, at least, of the rolls having 25 a yielding covering so constructed and arranged that any damaged portion thereof may be quickly and easily replaced by a new section of covering without removing either roll from the machine or interfering in any 30 way with any part of the machine other than the securing means for the damaged section of covering to be replaced or repaired.

Further objects of my invention are to so 35 mount the compressible covering of the roll as to protect it so far as possible from injury due to its spreading when under heavy pressure, and to so mount the covering of the roll that it will be propelled without danger 40 of slipping on the roll.

Still further objects and advantages of my invention will become obvious as the description proceeds.

In the accompanying drawings I show

what I now believe to be the most desirable 55 embodiment of my invention. It is obvious, however, that changes may be made in the specific construction shown without departing from the spirit of my invention.

In the said drawings, Figure 1 is a longitudinal elevation of a pair of rolls, the upper roll having a yielding covering and the lower roll being made of solid metal with an unyielding surface. Fig. 2 is a longitudinal 60 sectional view of the upper roll. Fig. 3 is a 65 cross section of the upper roll on line 3-3 of Fig. 1. Figs. 4 and 5 are perspective views of the outer and inner surfaces, respectively, of one of the removable lags of the upper roll. Fig. 6 is an end view of the 70 upper roll.

Similar reference characters refer to similar parts throughout the several figures.

The compressible roll comprises a rigid metal core 1, the ends of which are reduced 75 to form gudgeons 2 which are to turn in suitable bearings in the machine. Between the gudgeons the core 1 is of polygonal cross section, it being shown as octagonal, although the number of sides may obviously 80 be different if desired. Mounted upon each face 3 of the polygonal core is a lag 4 composed of a rigid metallic body portion 5, covered on its outer face with a suitable covering or layer 6 of some relatively soft yielding and compressible material, preferably 85 rubber. This covering may be attached to the body portion 5 of the lag by cementing, by forming ribs on the body portion to engage suitable corresponding ribs on the cover, 90 or in any other suitable manner.

To prevent lateral or longitudinal displacement of the lags on the core, the body portion 5 of each lag has a projecting rib 7 which fits snugly into a recess or groove 8 95 in the corresponding face of the core. The contacting longitudinal edges of adjacent lags are beveled and fitted so that no opening is left between them, and the outer surfaces of the compressible coverings 6 are so 100 curved that, when mounted on the core 1, the whole forms a perfect cylinder, as shown in Fig. 3. It is obvious that, because of the polygonal shape of the core, the line of action of the propelling force exerted by the 105 core on the lags as the roll is revolved is not tangent to the surfaces of the core and lags as would be the case were the core cylin-

drical; there is, therefore, a certain amount of action between the core and lags due solely to the peculiar shape of the core. Another advantage of a polygonal core is that the contacting surfaces of the lags and core are plane surfaces and, therefore, easily fitted; the lags are more easily and cheaply manufactured too than would be the case were their inner surfaces curved or irregular.

10 Each end of each lag is recessed at 9 to accommodate a suitable cap 9^a, screws being passed through each cap and the corresponding reduced end of the body portion of the lag and into the core to coöperate with the ribs 7 and grooves 8 in holding the lags securely in place. The caps 9^a are substantially segmental in form, and correspond in angular amplitude, to the lags with which they are associated. The caps 9^a 15 preferably of uniform width exert a clamping action on the lags, spreading the pressure of the screw heads out across the entire width of the ends of the lags, thereby holding the lags more firmly and evenly in place than the screws alone could do. The outer edges of the caps 9^a are curved so that each set of caps forms a slightly projecting circular peripheral wall abutting against the ends of the compressible coverings of the lags.

15 To limit the end play of the roll in its bearings and, incidentally, to give a finished appearance to the ends of the roll, a collar 10 is slipped over each gudgeon against the corresponding end of the polygonal section of the core and fastened in place by screws or otherwise. The lags are slightly shorter than the polygonal section of the core so that the collars 10 are held slightly 20 away from the ends of the lags 4 and caps 9^a, as shown in Fig. 2. This permits any lag to be removed and replaced without loosening either collar. The caps 9^a project radially to form abutting walls for the compressible coverings of the lags. This protects the ends of the compressible coverings and prevents their spreading endwise and cracking or rupturing when a bunch of the material being operated upon is passing between the rolls at or near one end of the roll.

15 The second roll 11, shown below in Fig. 1, is preferably formed of an integral piece of metal. Its central portion 12 is cylindrical to coöperate with the cylindrical surface of the compressible roll and its ends are reduced to form suitable gudgeons as

in the case of the compressible roll. A small portion of each end of the central portion 12 is reduced slightly in diameter to 60 provide suitable recesses 13 which accommodate the caps 9^a when the rolls are pressed together. One or both rolls may be positively driven in any suitable manner. It is obvious that the replacement of a damaged portion of the compressible covering 6 involves the replacement of only those lags which have been injured and that such replacement may be easily and quickly accomplished. Furthermore there is a great saving in expense over that involved in the replacement of a complete roll when a portion only of its covering has been damaged.

I claim,

1. A squeeze roll comprising a core, an 75 annular series of detachable lags carried by said core in interlocking relation therewith, each lag consisting of a body portion and a compressible covering, with the outer surfaces of said body portions curved to prevent an unbroken cylindrical surface.

2. A squeeze roll comprising a core, lags mounted on the core, and an annular series of segmental attaching devices for the ends of said lags, corresponding in number to 85 the number of said lags, and constituting annular flanges surrounding the ends of said lags.

3. A squeeze roll comprising a core, lags carried longitudinally by said core in interlocking relation therewith, and each having a compressible outer surface terminating short of the end of the lag, and means carried by each lag beyond the ends of said compressible surface for securing said lags 95 to the core, said means constituting annular flanges at each end of said compressible surface to prevent the spreading thereof.

4. A squeeze roll comprising a core, lags carried by said core in interlocking relation therewith, with their longitudinal surfaces in contact and their outer surfaces forming an unbroken cylindrical surface, the ends of said lags being cut away to provide recesses, and caps disposed within said recesses, and projecting above the outer surfaces of said lags to form annular flanges at each end of the roll.

Dated this 13th day of July 1912.

ARTHUR J. CHARLTON.
